UNITED STATES PATENT OFFICE

CLARENCE E. HAWKE, OF METUCHEN, NEW JERSEY, ASSIGNOR TO THE CARBORUNDUM COMPANY, OF NIAGARA FALLS, NEW YORK, A CORPORATION OF PENNSYLVANIA

FURNACE WALL CONSTRUCTION

Application filed May 2, 1923, Serial No. 636,146. Renewed October 24, 1929.

This invention relates to furnace wall constructions, and is particularly adapted to be used around the combustion chamber of a furnace. There is a growing tendency to work furnaces at extremely high rates of combustion. Under the increased temperatures resulting from such practice, the setting quickly burns out and when coal is used as a fuel, the fused ash reacts with the brick-work and destroys the setting in a very short time. This is especially true with low grade coal, and when such fuel is used it is impossible to maintain heavy furnace loads regularly because of the rapid deterioration of the brickwork.

I overcome this difficulty by providing a furnace wall lining of refractory material having relatively high heat conductivity and means for cooling the back of the material. The preferred material is silicon carbide. Silicon carbide not only is a very good heat resisting refractory, but has a relatively high heat conductivity, so that the heat is conducted away from the face of the material which is exposed to the flame, whereby such face is kept at a sufficiently low temperature to prevent spalling and damage by the heat. The silicon carbide also has a low porosity, so that there is little, if any, leakage of air through it. The wall refractories are preferably cooled by means of cooling air ducts, and the cooling air, after passing behind the refractory furnace lining, may be supplied to the fuel bed as combustion air, thus increasing the efficiency of the furnace by providing preheated air for combustion.

In the accompanying drawings, illustrating more or less diagrammatically my invention as applied to a coal-fired furnace.

Figure 1 is a sectional elevation through a furnace taken on the line I—I of Figure 2;

Figure 2 is a sectional elevation through the furnace taken on the line II—II of Figure 1;

Figure 3 is a section through another type of furnace, the air being supplied to the furnace above the grate, and

Figure 4 is a section of the furnace wall on the line IV—IV of Figure 3.

In the embodiment of my invention illus-

trated in Figures 1 and 2, cooling air is supplied to the furnace walls by any suitable means, such as blowers, not shown, through air pipes or openings 2; or the air may be drawn by induced draft. Air from the pipes 55 2 passes through ducts 3, in the furnace walls. These ducts preferably extend not only through the side walls 4, but also through the bridge wall 5, and terminate in outlets 6 below the grate 7.

Plates 8 or brickwork of silicon carbide form the wall between the ducts 3 and the interior of the furnace, since this material is non-porous, very refractory, and possessed of a very high heat conductivity.

In Figures 3 and 4, I have illustrated my apparatus as applied to another type of furnace wherein similar parts have been given the same reference character with the letter "a" suffixed. In this embodiment a conventional hopper type stoker is illustrated in chain lines and perforated blocks 9 are provided for introducing the air above the grate. The blocks 9 form a part of the combustion chamber walls and air is preferably supplied 70 to them after it has passed through the air ducts 3a behind the refractory plates 8a. Air is supplied to the ducts 3a from below the grate through an inlet 10 and its direction of travel is clearly indicated by arrows. I have 75 found that the use of the refractory plates 8a above the perforated tuyère blocks 9 materially improves furnace conditions both from a standpoint of operating efficiency and long life.

It will be apparent that in both forms of the invention illustrated the combustion chamber has silicon carbide walls which not only extend within the zone of the fuel bed, but a substantial distance above such zone. 90 As previously pointed out, when a poor grade of coal is used the fused ash reacts with the brick work and destroys the setting in a very short time. This is particularly true in furnaces under boilers that are highly over-rated, it having been found that the brick work above the fuel bed is destroyed prior to that portion in contact with the fuel bed. This results from the continual erosion of the side and bridge walls by the flow of deposited 95 100

ash which literally runs down over these walls in a molten condition. By the present invention I have overcome this difficulty. The portion of the silicon carbide walls within the zone of the fuel bed is maintained at such a low temperature that clinkers will not adhere thereto, while the portion of the silicon carbide walls extending above the fuel bed is also cooled so that they are protected from the destructive action of the fluid ash.

10 The invention has many advantages and is particularly valuable where furnaces are worked under severe conditions, such as heavy rating or low grade fuel, as it maintains the 15 furnace setting for a long period, with resulting economy in operation and freedom from care.

While I have shown and described certain preferred embodiments of my invention it will 20 be understood that the invention is not limited to these precise embodiments, but that it may be otherwise embodied within the scope of the appended claims.

I claim:

25 1. In a furnace, a combustion chamber, said combustion chamber having side walls and a bridge wall provided with facings of silicon carbide, said silicon carbide facings having many times the thermal conductivity 30 of fire-clay refractory material and extending within the zone of the fuel bed and a substantial distance above said zone, and a duct back of said facings through which cooling air is circulated in contact with the rear 35 walls of the facings throughout the major portion of the area thereof, a portion of said facings above said zone being imperforate, and a portion thereof within said zone being perforate, said duct delivering to said perforate portion whereby the cooling air which circulates through said duct is conducted to the fuel bed through said perforate portion in a highly preheated condition.

40 2. In a furnace, a main wall structure, a combustion chamber defined thereby, said main wall structure having certain portions thereof forming the walls of the combustion chamber of non-metallic refractory material of many times greater thermal conductivity than fire-clay refractory material, said portions extending both within the zone of the fuel bed and a substantial distance above said zone, and a duct back of said portions of high thermal conductivity providing 45 an elongated circulating path covering substantially the entire area of such portions above the zone of the fuel bed for cooling the slag in contact with the inner surfaces of said portions to thereby form a protective 50 covering therefor, the portions above the zone of the fuel bed being imperforate.

55 3. In a furnace, a main wall structure, a combustion chamber defined thereby, said main wall structure having certain portions thereof of refractory material forming the

walls of the combustion chamber and of many times greater thermal conductivity than fire-clay refractory material, said portions extending both within the zone of the fuel bed and a substantial distance above said zone, 70 and a duct back of said wall through which cooling air is circulated in heat conducting relationship to the portions of high thermal conductivity for cooling said portions to prevent the adherence of clinkers thereto, and the portions within said zone being perforate to permit the passage of the preheated air to the fuel zone.

4. In a furnace, a main wall structure, a combustion chamber defined thereby, said main wall structure having certain portions thereof of non-metallic refractory material forming the walls of the combustion chamber and of many times greater thermal conductivity than fire-clay refractory material, 80 said portions extending both within the zone of the fuel bed and a substantial distance above said zone, a duct back of said wall through which cooling air is circulated in heat conducting relationship to the portions of high thermal conductivity for cooling said portions to prevent the adherence of clinkers thereto, means for securing forced circulation of air through the duct, and means for conducting the preheated air from said duct 85 to the combustion chamber.

90 In testimony whereof I have hereunto set my hand.

CLARENCE E. HAWKE.
